TIMBRE-CONTROLLER FOR ELECTRICAL MUSICAL INSTRUMENTS.

1,110,012.

Specification of Letters Patent. Patented Sept. 8, 1914.

Application filed August 7, 1905. Serial No. 273,202.

To all whom it may concern:

Be it known that we, MELVIN L. SEVERY, of Arlington Heights, in the county of Middlesex, State of Massachusetts, and GEORGE B. SINCLAIR, of Winthrop, in the county of Suffolk, in said State, both citizens of the United States, have made certain new and useful Improvements in Timbre-Controllers for Electric Musical Instruments, of which 10 the following is a full, clear, and exact description.

Our invention has for its purpose the construction of an improved device by means of which to vary the rates of electric impulses 15 communicated to the magnets of an electric musical instrument, for the purpose of changing the quality of musical sounds emitted, whenever desired. In those instruments where the sonorous bodies are strings, 20 we contemplate the change of the pitch and tone quality of said bodies, without altering their normal length or tension.

The instrument to which our invention is especially applied is of the piano type, and 25 the normal pitches of the strings under normal conditions correspond with the pitches usually associated with the respective keys of a piano. These pitches also correspond 30 respectively with the periodicities of the make-and-break or impulse-generating devices normally associated with the strings.

When, however, it is desired electrically to change the tone qualities given off by the strings, their actuating electromagnets have 35 pulsations of higher frequencies switched into them, with the result that they give off pitches the same as those of the pulsations, but higher than those normally associated with the strings and their corresponding 40 keys. These tones are of an entirely different quality from those produced under the aforesaid normal conditions. It is further to be noted that these new qualities are not harmonics having a more or less submerged 45 graver tone present, as in the case of the piano, violin and the like, but they are distinctly new qualities having distinctly new ground tones, which ground tones do not result from the length and tension of the 50 strings, but do result from the periodicities of the make-and-break or impulse-producing devices which are sending pulsations

into the electromagnets actuating the strings. Each of these new ground tones has its own system of harmonics. This distinction is vital and must not be confused with the so called harmonics or partial tones of other instruments, which are the result not of the substitution of a new ground tone, but rather of a change in the relative 55 prominence of the harmonics forming composite tones. Such tones are natural or unforced, whereas the new qualities we produce result from forced vibrations which determine with mathematical accuracy the 60 pitches of the ground tones. Such special type of our invention, wherein tuned strings are employed for the sonorous bodies, is set forth in the following description and in the drawings associated therewith. 65

Referring to the drawings forming part of this specification, Figure 1 is a side elevation of our device, showing in section a portion of the piano with which the same is designed to be connected, with other parts 75 illustrated in diagram. Fig. 1^a is a fragmentary front elevation of the piano-key bed showing the indicator and markings. Fig. 2 is a plan view of said device, with a part thereof represented as broken away. 80 Fig. 3 is a detail sectional view on the broken line X—X in Fig. 5 of the contact-blocks and supporting-board composing part of the timbre controller. Fig. 4 is a rear view, and Fig. 5 a face view, of same. 85

The reference numeral 1 indicates a contact-making device corresponding to the keyboard of the piano, and 2 is the part of the piano-key bed above which the piano-keys are usually located. 90

10 is one of the piano wires or strings; 95 20 are the electromagnets, one of which is in control of said wire, and the other shown is supposed to control the string next to the one shown.

The main part of this timbre controller consists of the curved board 85 supported from the piano-section 2 by the frames 86; said board having its surface covered with a large number of insulated contact-blocks 100 70 arranged in transverse and longitudinal rows. Contacting with these blocks are the brushes 72 fixed to the bar 71 which is supported by the arms 73 pivoted at 87 concen-

tric with the curvature of said board 85. A coiled spring 77 attached to an extension of said arm or arms 73 serves to counterbalance the bar 71 and the arms 73, and thereby ease the operation of shifting the position of the said bar and brushes with respect to the contact-blocks 70. To thus shift said bar and brushes, the bell-crank lever 78, 76 is pivotally supported upon the spindle 81 held by the piano-section 2, and is provided with an extension 76 engaging the arm 75 rigid with said arms 73. By swinging said lever to one side or the other, the brushes 72 are raised or lowered accordingly. The front end of said lever is connected with a block and pointer 79 slideable in a guide-way 80; and said pointer by means of suitable markings 79^a along the front of the piano, enables the operator to know at a glance to which marking to shift the pointer in order to locate the brushes 72 in contact with a certain row of contact-blocks 70 and produce a designated musical effect.

25 There are as many brushes 72 as there are electromagnets 20, and each brush is joined by a suitable lead-wire 74 to its proper magnet. To each block in the highest row of contact-blocks 70 a lead-wire 65 passes from a brush 41 contacting with the periphery of a toothed disk 40 by means of which the electric impulses are produced; the current coming thereto from the source of electricity 60 through the wire 61.

30 35 For the production of the normal tones on the musical instrument, the bar 71 remains with its brushes in touch with the highest row of blocks 70; then a key 1 being depressed, the current flows from the source 60 through the proper disk 40 to the appropriate block 70; thence through the brush in contact with the latter to the magnet in circuit therewith; from there through the wire 3 to the key 1, thence back to the source 60 through the wires 64, 62. Whichever key is thus depressed, the proper number of pulsations per unit of time is imparted to the magnet which controls the string designed to vibrate the same number of times; and 40 45 50 hence the piano strings all respond with their normal tones or quality.

55 60 To produce the tone qualities due to pulsations of higher frequency in the same strings, by imparting to the magnets pulsations timed to correspond to the fifths, octaves, etc., of their normal vibrations, the contact-blocks 70 are arranged as follows: As shown in Fig. 3, the board 85, which may be of wood or other insulating material, has 65 the blocks 70 affixed thereto both by cementing and by a nail or pin penetrating each block and projecting through, and for a short distance beyond the back of, said board. To the projecting ends of said pins or nails 90 are soldered wires 91 by means

70 75 80 85 90 95 100 105 110 115 120 125 130 of which the highest row of blocks 70 are electrically coupled with the rows below. The manner in which these rows are coupled is shown in Fig. 4, where each block or pin in the topmost row marked Normal is connected by the short wires 91 to a pin 90 in the row next below seven pins away; each pin of this last-named row is wired to the row next below five pins away, thereby making each block in this last row an octave distant (twelve semi-tones) from each connected block in the first row. In the same manner this third row has its pins wired to pins in the two lower rows seven and five blocks distant, and then finally to the lowermost row four blocks or pins away. As illustrated in Fig. 4, the pulsation producing devices 40, 41 adapted to produce pulsations equal in number to the vibrations of the C⁷ string, are coupled to the electromagnet 20 which actuates a string 10 of the pitch an octave lower, that is, C⁶; the brush 72 connected with said electromagnet being in touch with a block whose pin 90 is wired to the C⁷ pin in the Normal row. With all the brushes 72 thus positioned, each string 10 will have communicated thereto actuating impulses an octave higher in pitch. While this causes all the strings to vibrate on a higher pitch, it will at the same time cause them to emit absolutely new qualities; each change from one row to another of the blocks educating still other timbres, along with the expected changes in pitch.

100 For the sake of simplicity in illustration, the brush 72 is shown in Fig. 4 as though it were supported at its lower end, instead of at its upper end as shown in Fig. 1.

105 By moving the brushes 72 into touch with some other row of contacts 90, or to other rows not illustrated, any other desirable rates of pulsations can be delivered to the electromagnets. For example, if pulsations of the C⁷ frequency are switched to the F⁶ magnet, the string corresponding to this 110 magnet will be forced to vibrate with the C⁷ frequency, but giving a new ground tone which has its own system of harmonics. These intermediate transpositions give other effects, which in certain cases are desirable, 115 but which it is not deemed necessary to elaborate, since the invention consists broadly in means for effecting such transpositions, and in carrying out the novel method claimed, of producing new and unusual tone effects.

120 125 130 In forming the blocks 70, the preferred way is to take long strips of brass of a width equal to the size of the blocks, with holes drilled therein at what will afterward become the centers of the blocks, and cement and nail these strips side by side upon the board 85, but with a slight space between the strips filled in with a suitable non-conducting cement or other material. Then

when the cement has all hardened, these strips are cut or sawed through transversely, thus forming wholly separate blocks, and the sawkerfs all filled in with cement or other non-conducting material. This method of forming the blocks and of wiring them to each other provides an exceedingly economical and practical manner of doing what is otherwise a most expensive operation.

It is to be remembered that each of the toothed disks 40 before mentioned must be rotated uniformly and must be maintained in sensibly perfect synchronism with the sonorous body with which it is normally associated. No ordinary "governing" is of any avail, since variations in speed too slight to be detected by any other means impair or destroy both the loudness and the timbre of the tones. The synchronism for the best musical results must be so perfect as not to exhibit the slightest beat between the frequency of the current and that of the sonorous body it is intended normally to operate.

It is manifestly requisite to the obtaining of different musical timbres after the manner of our invention, that each current pulsator shall be practically perfectly synchronized with the sonorous body with which it is normally associated, if good musical results are to follow the switching of different frequencies of pulsations into the different magnets for we have discovered that a defect hardly noticeable in the tone emitted by a sonorous body energized by pulsations from the pulsator normally associated with it, will be greatly amplified when this sonorous body speaks in response to pulsations from any other pulsator. In view of this it will be seen that a change of speed in the rotative mechanism might easily render nugatory a change in the quality controller, for which reason the necessity of constant synchronism as a prerequisite to proper change of tone timbre will be perfectly apparent.

While some form of synchronizer, and one capable of producing perfect or substantially perfect timing of the pulsations, is essential to the attainment of the results herein set forth, the present invention is not restricted to any particular form of said device. Synchronizers suitable to the purpose are, however, set forth in our joint application Serial No. 563,437, filed May 25th, 1910, and in the sole applications of M. L. Severy, Serial No. 619,633, filed April 7th, 1911, and Serial No. 620,002, filed April 10th, 1911. As these are distinct inventions, and some of them sole inventions, they are not set forth or claimed in this application.

In our joint application, Serial No. 379,714 filed June 19, 1907, is further disclosure and description of features more or less in common with features of this present

application. To the extent that such matters are claimed in said application Serial No. 379,714 they are not claimed herein, but are reserved to said later application. Like reservation is also made as to matter common to the present application and to our joint applications Serial No. 745,400 filed January 31, 1913, and Serial No. 753,013 filed March 8, 1913, and not specifically claimed herein.

What we claim as our invention and for which we desire Letters Patent is as follows, to wit:

1. The combination with sonorous bodies tuned to notes of the musical scale, of impulse-producing and delivering means normally individual to each body, said impulses being equal in frequency respectively to the vibrational frequency of the fundamental of the sonorous body normally associated therewith, and means operative at will for delivering to said bodies impulses of frequencies higher than the fundamental frequencies of said bodies.

2. The combination with sonorous bodies tuned in musical relationship, of means for normally delivering to said bodies impulses equal in frequencies to the vibrational-frequencies of their fundamentals, and means operative at will for delivering to certain of said bodies impulses normally delivered to others of said bodies having higher pitches, thereby producing tones of different qualities.

3. The combination of sonorous bodies tuned in musical relationship, electromagnets for actuating said bodies, means for delivering electric pulsations to said electromagnets corresponding in frequencies to the vibrational-frequencies of the fundamentals of their associated bodies, and means provided with an indicator for switching to certain of said electromagnets the pulsations normally delivered to other electromagnets associated with the bodies of higher pitches.

4. The combination of sonorous magnetically attractive bodies tuned in musical relationship, electromagnets for vibrating said bodies, means for delivering electric pulsations to said electromagnets, the pulsations delivered to each electromagnet corresponding in frequency to the fundamental vibrations of the body associated therewith, and means operative at will adapted for delivering to certain of said electromagnets electric pulsations of frequencies higher than the fundamental frequencies of their associated sonorous bodies.

5. The combination of sonorous bodies tuned in musical relationship, electric means for vibrating said bodies, and switching means for said electric means, said switching means comprising a multiplicity of contacts arranged in transverse and longitudinal rows, brushes corresponding in number

and arrangement to said transverse rows, means for moving said brushes along said transverse rows, and connections between said brushes and electric means and between the latter and the contacts in one of the longitudinal rows, the last-mentioned contacts being wired to certain contacts in each of the other longitudinal rows.

6. The combination of sonorous bodies 10 tuned in musical relationship, electric means for vibrating said bodies, and switching means for the latter, said switching means comprising a supporting frame, a curved board, rows of connected contacts on said board, a bar and arms pivoted to said frame, brushes carried by said bar in touch with one row of said contacts, a spring for counter-balancing said arms and bar, and a lever and connections therefrom to said arms and 20 bar to move the latter vertically when said lever is swung horizontally, said brushes and also the contacts of one of said rows being connected with said electric means.

7. The combination of sonorous magnetically attractive bodies, electromagnets for actuating the same, means for producing properly-timed electric pulsations for said electromagnets, and means operative at will for directing to said electromagnets pulsations of higher frequency than those normally delivered thereto and thereby changing the quality of the tones produced.

8. A musical instrument comprising electromagnetically attractive sonorous bodies, 35 and electromagnets adapted for vibrating the same, means for varying the timbre of the sounds emitted by said bodies comprising devices adapted for delivering to said electromagnets pulsations in synchronism 40 both with the fundamentals of said bodies and also at will with other periodicities in musical relation with such fundamentals, and means under the control of the player for determining which of said pulsations shall be delivered to the electromagnets.

9. A musical instrument comprising tuned sonorous bodies, means for electromagnetically attracting said bodies, and means for interrupting the magnetic attraction of each 50 body with a frequency corresponding to its fundamental rate of vibration, or also at will with frequencies greater than the same but bearing musical relation thereto, whereby a plurality of timbres can be educed from the same body.

10. The combination with a plurality of sonorous bodies respectively tuned to definite musical pitches, of electromagnetic 60 means for independently eliciting from each of said bodies at will, a musical tone of pitch other than that to which such body is tuned.

11. The combination of a plurality of sonorous bodies; electromagnets for their actuation; means for delivering to said 65 magnets pulsations of frequencies corre-

sponding to the normal frequencies of vibration of their associated sonorous bodies; and means controllable by the operator for independently delivering to each of said magnets at will, pulsations of a frequency greater than the frequency of vibration to which its associated sonorous body is tuned.

12. A musical instrument comprising 70 sonorous bodies; means for vibrating them; and means for changing their tone quality at will in a definite manner and to a predetermined extent, while maintaining said bodies free or open throughout their full vibrational length.

13. A musical instrument comprising 80 magnetically attractive sonorous bodies; electromagnets for actuating them; a source of electric current; make-and-brake devices timed to the fundamental vibrations of said bodies; connections between said source, devices and electromagnets; and means, operative at will, for delivering to the electromagnets of selected bodies the pulsations of frequencies normal to others of said bodies.

14. The art of educing from a tuned 90 sonorous body a tone of different pitch and quality from that given off by such body when vibrating freely, which consists in electrically imparting to said body vibration of a frequency other than that which produces its fundamental tone.

15. The art of educing from a tuned sonorous metallic body a tone of different pitch and quality from that given off by such body when vibrating freely, which consists in imparting to said body vibration of a frequency different from that which produces its fundamental tone.

16. The art of educing from a tuned sonorous metallic body a tone of different 100 pitch and quality from that given off by such body when vibrating freely, which consists in electrically imparting to said body vibration of a frequency different from that which produces its fundamental tone.

17. The art of producing musical tones, which consists in imparting to a tuned sonorous metallic body, vibration of a frequency greater than that which produces its fundamental tone, and thereby educing a tone quality unlike that emitted by said body when vibrating with the frequency which produces said fundamental tone.

18. The art of producing musical tones, which consists in electrically imparting to a tuned sonorous body vibrations of a frequency materially greater than those which produce its fundamental tone, and thereby educing a tone quality unlike that of said fundamental tone.

19. The art of eliciting at will from a tuned sonorous metallic body any one of a plurality of tone qualities, which consists in causing in said body vibrations which produce primarily and as a ground tone 130

any one of the upper harmonics of the natural fundamental tone of such body when vibrating freely.

20. The art of eliciting at will from a tuned sonorous body, any one of a plurality of ground tones, which consists in electrically causing in said body vibrations which are of the frequency of a selected one of the natural harmonics of said body when the same is vibrating freely.

21. The art of producing tones of various timbres, which consists in forcing a given sonorous body to vibrate at a frequency corresponding to any selected higher harmonic of said body, and thereby causing said body to give off an entirely new ground tone accompanied by its own set of harmonics.

22. The art of producing tones of various timbres, which consists in electrically forcing a given sonorous body to vibrate at a frequency corresponding to some harmonic of said body, and thereby causing said body

to give forth a ground tone different from its normal or usual fundamental and accompanied by its own set of harmonics.

25

23. The art of eliciting musical tones, which consists in producing in electro-magnet-circuits pulsations equal in their frequencies to the frequencies of vibration of magnetically attractable sonorous bodies tuned to the musical scale, and causing such pulsations, of higher frequency, to be delivered to an electromagnet arranged to attract a sonorous body whose fundamental tone is produced by vibrations of lower frequency.

30

35

In testimony that we claim the foregoing invention, we have hereunto set our hands this 21st day of July, 1905.
